UNITED STATES PATENT OFFICE.

IRA A. WEAVER, OF SPRINGFIELD, ILLINOIS, ASSIGNOR TO THE WEAVER MANUFACTURING COMPANY, OF SPRINGFIELD, ILLINOIS, A CORPORATION OF ILLINOIS.

SPARK PLUG.

Application filed March 1, 1920. Serial No. 362,395.

To all whom it may concern:

Be it known that I, IRA A. WEAVER, a citizen of the United States, residing at Springfield, in the county of Sangamon and State 5 of Illinois, have invented certain new and useful Improvements in Spark Plugs, of which the following is a specification.

My invention concerns cleanable spark-plugs for use with internal-combustion engines or motors which are subject to more or less fouling and possible short-circuiting by the residual carbon deposited thereon remaining from the lubricating oil and the fuel.

One object of the invention is the mounting of one of the terminals or sparking points in such a way, as by pivoting or hinging it, so that it may be temporarily shifted away from its companion, thus rendering 15 easily accessible the spaces or cavities of the plug most likely to contain or harbor the objectionable carbon and possibly other fouling substances.

Furthermore, a plug which will spark or 20 arc properly in the open, as when unscrewed from the motor and resting on its top surface, and thus present the appearance of being wholly satisfactory and in operative condition, will not necessarily perform its 25 fuel ignition function efficiently or effectively, or, perhaps it may not spark at all, when it is in place in the engine and subjected to the compression of the explosive mixture. Therefore, such a test of a plug 30 is unreliable and may be wholly misleading. Accordingly, one of the prime purposes of 35 this invention is to provide a spark-plug structure which will permit it to be tested in the open air in such a way that if the test 40 is satisfactory there is all reasonable assurance that the plug will function properly when subject to the engine-cylinder compression. This may be done by making one of 45 the spark-plug wires or points adjustable so that the gap between the points may be lengthened during the test to compensate for the absence of compression. If the arc 50 jumps such test gap in the open air there is reasonable certainty that it will properly jump the shorter service-gap under compression conditions. Accordingly, in the improved plug, the movable terminal has two 55 definite positions, the one forming a shorter service-gap with the complementary terminal, and the other a longer test-gap, the mov-

able terminal being also capable of being shifted still further away from the companion fixed terminal to facilitate the cleaning of the plug as a whole.

To enable those skilled in this art to fully 60 understand this invention I have illustrated embodiments of the same in the accompanying drawing forming a part of this specification and to which reference should be had in connection with the following detailed 65 description.

In this drawing, throughout the several views of such sheet, like reference characters refer to the same parts.

Figure 1 is an elevation of the preferred 70 embodiment of the invention;

Figure 2 is an enlarged elevation of the end portion of such spark-plug with the outer threaded metal sleeve or skirt broken away to more clearly illustrate the internal 75 construction;

Figure 3 is a bottom plan view of the structure of Figure 2;

Figure 4 is a fragmentary elevation of the lower portion of the plug showing more 80 clearly the pivotal or hinge mounting of the movable terminal;

Figure 5 is a fragmentary elevation of the other side of the plug;

Figure 6 shows partly in elevation and 85 partially in section a different form of spark-plug incorporating a modified structure and shows the plug screwed into position in a portion of the engine or motor; and

Figure 7 is a bottom plan view of the plug 90 of Figure 6 removed from the engine and with the movable terminal temporarily swung away to facilitate the carbon cleaning operation.

Referring first to the species of plugs 95 illustrated in Figures 1 to 5 inclusive, it will be observed that the device comprises a hollow metal main-body 10 having a hexagonal portion 11, a cylindrical part 12, and an externally-threaded skirt section 13 100 adapted to be screwed into a correspondingly-threaded hole in the engine or motor, a flat shoulder 14 being present between the larger part 12 and the portion 13 of reduced diameter. Such body receives within 105 it a porcelain or other suitable insulation sleeve 15 covering and protecting an inner terminal 16 which at its one end projects beyond the porcelain element to form a spark terminal and at its other protruding 110

end is fitted with the ordinary means 17 for the attachment thereto of an electrical conductor. So far as thus described, this is an ordinary spark-plug, but it may be noted 5 that the hole 18 through the main metal body is eccentric to its outer surfaces, thus making one portion 19 of its wall thicker than the diametrically-opposite portion 20 of the same wall. The complementary electric terminal 21 comprises a bent spring wire of U-shape with one leg 22 longer than the other leg 23, the intermediate connecting portion being somewhat bowed at 24 as illustrated in Figure 3. The part 22 is de- 10 sirably copper-coated to prevent undue or excessive corrosion and occupies a cylindrical-hole or bearing 25 of the same diameter drilled lengthwise the plug from its end in the thickest part 19 of the eccentric threaded skirt or apron. Such hole communicates at its upper end with a relatively-shallow cavity 26 of large bore extended radially inwardly in the part 19 and in this recess the end section of the wire is bent 15 laterally or crimped at 27 to retain the wire from lengthwise movement in its bearing 25. As is shown most clearly in Figures 2, 3, and 5, the edge of the thinner part 20 of the metal sleeve 13 is supplied with two 20 spaced notches or depressions 28 and 29 either one of which is adapted to receive the end of the leg 23 of the terminal to retain 25 it in fixed position until intentionally shifted therefrom, it being understood that the terminal has sufficient resiliency to permit such movement.

The construction is such that when the part 23 of the movable terminal is in the retaining notch 28, the spark-gap or arcing 30 space between the terminals will be that which is proper for service and hence, may be aptly termed, the service-gap. When the same portion of the shiftable terminal is in the other depression 29, as is indicated 35 in dotted lines in Figure 3, and in full lines in Figure 5, the spark-gap or so-called test-gap between the terminals will be somewhat greater and will have such relation to the service-gap that if the plug will arc 40 properly over such test-gap in the open atmosphere it will spark efficiently over the service-gap when in place in the engine and subjected to the usual explosive-mixture 45 compression.

If it is desired to clean the plug, the oscillatory terminal may be rocked to an extreme outer position, as is also depicted in 50 dotted lines in Figure 3, thereby exposing the terminals themselves for cleaning, but more especially the space between the porcelain insulator 15 and the inner surface of the threaded skirt or apron portion 13.

The readily-accessible cavity or aperture 55 26 affords easy means for the introduction of a suitable tool to provide the retaining

crimp 27 in the terminal wire when the latter is first inserted in place, and for straightening out such bend if desired to permit the withdrawal of the wire and its substitution by another.

In Figures 6 and 7 a somewhat different construction of plug is presented. This has only one length of spark-gap and hence does not embody the feature of test and service gaps specified above, but it has one of its terminals movable to facilitate the cleaning operation. The plug is like the one of the other figures except that, instead of incorporating the terminal 21 and its mounting and retaining or position determining 60 notches, the outer threaded surface of the thickest part of the metal skirt has a longitudinal groove 30 which at its upper end connects with a cross or horizontal bearing 31 in which a laterally-bent journal part 32 65 of the movable terminal 33 is rockingly mounted, an intermediate portion 34 of the terminal normally occupying the groove 30 and retained therein by the wall of the engine or motor in which the plug is screwed, 70 all as is fully indicated in Figure 6. Under these conditions there is a normal service-gap of correct length between the ends of the two terminals, but as soon as the plug is removed from the engine, its outer terminal is free to be swung away from the inner terminal sufficiently to give plenty of room for the carbon-removing operation. When the plug is in service, however, such outer terminal is firmly and securely held in 75 proper position without danger of dislodgment or mal-adjustment.

In both of these embodiments the portion of the movable terminal in contact with the metal sleeve may be copper or otherwise 80 plated to reduce or eliminate the tendency to corrosion at such point, or, if preferred, a sleeve of suitable metal different from that of the apron or skirt of the plug, may be inserted in the bearing aperture thereof, 85 thus operating as a bushing of different metal between the movable terminal and the main-body of the plug.

The invention is obviously not limited and restricted to these particular embodiments as is indicated by the scope of the appended claims, and these particular plugs have been shown and described by way of example only. It will be understood, therefore, that many other structures differing 90 from these more or less in mechanical details may be made incorporating this invention without departing from the substance and essence of the latter and without the sacrifice of any of its substantial benefits and advantages. For example, it is not necessary that the one terminal be movable toward and from the other so long as the plug may be caused to have a plurality of gaps of different lengths.

I claim:

1. A spark-plug for internal-combustion engines in which one of the terminals is rockingly adjustable relatively to the companion terminal to provide a plurality of spark-gaps of predetermined different lengths between the terminals, substantially as described.

2. A spark-plug for internal-combustion engines having a pair of terminals one of which is movable toward and from the companion terminal with means to lock it automatically in two predetermined positions, the one position forming a service-gap and the other position a test-gap of different length, substantially as described.

3. A spark-plug for internal-combustion engines having a pair of terminals movably mounted relatively to one another to provide a predetermined service-gap for use under compression and a longer predetermined test-gap for use in the open atmosphere of a length to compensate for the absence of compression, with means to lock the terminals automatically in the two service and test positions, substantially as described.

4. A spark-plug for internal-combustion engines having a terminal, a companion terminal rockingly mounted in the plug to vary the length of spark-gap between the terminals, and a layer of metal different from that of said movable terminal interposed between the same and its bearing in the plug, substantially as described.

5. A spark-plug for internal-combustion engines having in combination a terminal, a depending threaded skirt with a longitudinal bearing therein and a plurality of notches, and a movable terminal rockingly

mounted in said bearing and having a portion adapted to engage any one of said notches, to provide the spark-plug with a plurality of spark-gaps of different lengths, substantially as described.

45

6. A spark-plug for internal-combustion engines having in combination a terminal, a depending threaded skirt of varying thickness with a longitudinal bearing therein at its thickest part and a plurality of notches therein at its thinner part and a movable terminal rockingly mounted in said bearing and having a portion adapted to engage any one of said notches to provide the spark-plug with a plurality of spark-gaps of different lengths, substantially as described.

50

7. A spark-plug for internal-combustion engines having in combination a terminal, a depending threaded skirt with a longitudinal bearing therein and a plurality of notches in its edge, a U-shaped movable terminal having one leg thereof rockingly mounted in said bearing and the other leg adapted to engage any one of said notches to provide the spark-plug with a plurality of spark-gaps of different lengths, substantially as described.

60

8. A spark-plug for internal-combustion engines having a lengthwise channel in its skirt rockingly accommodating one of the spark-plug terminals, said plug having an aperture intersecting said channel to facilitate the securing of the terminal in said channel and its removal therefrom by giving access thereto to permit bending of the terminal wire for its retention in place or to permit its removal from the plug, substantially as described.
